UNITED STATES PATENT OFFICE.

HERBERT J. STRAKER, OF NORTH ATTLEBOROUGH, MASSACHUSETTS,
ASSIGNOR TO ATTLEBORO MANUFACTURING CO., OF ATTLEBOROUGH,
MASSACHUSETTS.

DESIGN FOR A HANDLE FOR PAPER-CUTTERS OR SIMILAR ARTICLES.

SPECIFICATION forming part of Design No. 33,185, dated September 11, 1900.

Application filed July 10, 1900. Serial No. 23,167. Term of patent 3½ years.

To all whom it may concern:

Be it known that I, HERBERT J. STRAKER, a citizen of the United States, residing at North Attleborough, in the county of Bristol and State of Massachusetts, have invented and produced a certain new and original Design for the Handle for a Paper-Cutter or Similar Article, of which the following is a specification, reference being had therein to the accompanying drawings.

My invention consists in the ornamentation and configurations hereinafter described, the leading features of which are the novel outline of the handle and its ornamentation, including its beading arrangement.

The drawings present in Figure 1 an obverse view of my handle, and Fig. 2 a vertical section of the same.

In detail, A represents the head, B the stem, and C the base, of my handle. The head A is a polygon in cross-section, with its plain sides 11 tapering as they extend downwardly, having along the side intersections

vertical series of spherical beading 22. The upper portion of the head bears a crest of 25 foliates 3. The stem B bears a flower 4, inclosed on either side by upwardly-directed foliated scrolls 55. Beneath this the stem is outlined by a vertical bar 6 along the handle-axis, with oppositely-disposed scrolls 77 on 30 either side. The base C has a swelled outline covered by a cluster of leaves and foliates 8.

Having described my invention, what I claim as new, and desire to secure by Letters 35 Patent, is—

The design for a handle for paper-cutters or similar articles as herein shown and described.

In testimony whereof I have affixed my signature in presence of two witnesses.

HERBERT J. STRAKER.

Witnesses:
